(57) CLAIM

I claim the ornamental design for the water spout, as shown and described.

DESCRIPTION

FIG. 1 is a perspective view of the water faucet embodying my design;

FIG. 2 is a side elevational view of the water faucet as shown in FIG. 1, the other side being a mirror image;

FIG. 3 is a top plan view of the water faucet shown in FIG. 1; and,

FIG. 4 is a bottom view of the water faucet shown in FIG. 1.
